UNITED STATES PATENT OFFICE

FRANK J. MORAVEK, OF HOLYROOD, KANSAS

CAN HOLDER

Application filed September 10, 1927. Serial No. 218,665.

The present invention relates to can holders and is particularly adapted for holding a milk can on the running board of an automobile.

Objects of the invention are simplicity and cheapness of construction, effectiveness in operation and neatness of appearance.

In the drawings:

Figure 1 is a sectional view showing my device as used on the running board of an automobile to clamp a milk can thereupon, showing the can broken away.

Figure 2 is a perspective view of the clamping device forming the subject matter of the invention.

Referring to the drawings in detail, 10 designates a support, as a running board of an automobile. 11 is a milk can placed thereon. 12 is the can holder which comprises a body portion 13, from which project pairs of parallel spaced arms 14 and 15 adapted to receive therebetween the support, as a running board, upon which the can is supported. The ends of the arms 14 and 15 enlarge at the end adjacent the body 13 to form abutments 16. The sets of clamping arms 14 and 15 are spaced apart horizontally as are also the abutment shoulders 16. Projecting from the body portion and lying between the abutments 16 is an arm 17 having a portion 20 projecting upwardly to form a channel 18 adapted to receive the edge of the can. Threaded into the arms 14 at their free ends are clamp screws 19 adjustable to clamp the running board between the arms 14 and 15. Likewise, the arm 17 is provided with a clamp screw 21 adapted to clamp the rim of the can against the abutment shoulders 16.

When it is desired to clamp a can to the running board of an automobile, all that is necessary is to mount the device on the running board with the running board lying between the arms 14 and 15 and then turn the handles of the screws 19 to clamp the device in place. The can is then placed on the running board with one side of the wall which projects below the bottom of the can lying against the shoulders 16. The screw 21 is then tightened so that the wall of the can is

bound between the shoulders 16 and the clamp screw 21 as shown in Figure 1.

Having described the invention what I claim is:

A holder comprising spaced parallel arms, 55 enlargements formed with the arms and connecting the latter at one end in superposed pairs, a body portion connecting the enlargements together, the opposite ends of said arms being free, an arm formed with the body portion, an upwardly projecting portion formed in the last mentioned arm and being spaced with respect to the body portion to provide a channel, said enlargements providing shoulders, a screw member threadedly secured in the upwardly projecting portion and being adapted for engagement with the depending rim of a container received in said channel to force said rim against said shoulders, and 60 means carried by the lower arms of the pairs, 70 for securing said holder to a support.

In testimony whereof I affix my signature.
FRANK J. MORAVEK.
